[57] CLAIM

The ornamental design for a panel spacer pad, as shown and described.

DESCRIPTION

Fig. 1 is a top plan view of a panel spacer pad showing our new design;

FIG. 2 is a front elevational view thereof, with the rear elevational view being a mirror image;

FIG. 3 is a bottom plan view thereof; and

FIGS. 4 and 5 are respectively left and right side elevational views thereof.

FIG. 1

FIG. 2

FIG. 3

FIG. 4

FIG. 5
